(57) **CLAIM**

The ornamental design for a shoe, as shown and described.

DESCRIPTION

FIG. 1.1 is a front view of a shoe;

FIG. 1.2 is a rear view of a shoe;

FIG. 1.3 is a top view of a shoe;

FIG. 1.4 is a right side view of a shoe;

FIG. 1.5 is a bottom view of a shoe;

FIG. 1.6 is a left perspective view of a shoe; and

FIG. 1.7 is a left side view of a shoe.

The broken lines in the figures are for the purpose of illustrating portions of a shoe and form no part of the claim.
